UNITED STATES PATENT OFFICE.

FOSTER J. HULL, OF HAGERSTOWN, MARYLAND, ASSIGNOR TO PANGBORN CORPORATION, OF HAGERSTOWN, MARYLAND, A CORPORATION OF MARYLAND.

SAND-BLAST BARREL.

Application filed January 5, 1926. Serial No. 79,301.

The invention relates to an abrading machine which though other abrasives than sand are generally used at the present time, is known to the trade as a sand blast machine.

The machine consists of a rotary container or barrel in which castings or other articles to be cleaned or otherwise abraded, are placed, the rotation of the barrel serving to present them in turn at the surface of the load and expose them to the blast. The barrel, and driving means, etc., are preferably enclosed within a casing and the barrel has at its axial ends, openings for the admission of the abrasive stream of air under pressure and abrasive, known as a sand blast which is directed in any suitable manner at the exposed surface of the load, preferably as described in my co-pending application, Serial No. 79,300, filed January 5, 1926, the machine, as shown, being of the direct pressure type.

The barrel or rotary container is filled to a little less than half of its full internal volume or capacity with castings to be cleaned, and rotated, the sand blast being directed into the barrel by way of the opening, the centre of the blast being in accordance with the usual practice applied to the centre of the exposed surface of the load.

While the blast or abrasive stream is applied or intended to be applied to the centre of the exposed surface of the load, the fact is that a considerable portion of the abrasive particles are during the entire operation due to divergence of the stream and splashing, moving at high speed more or less in the direction of the axis of the barrel, impinging against the ends of the barrel with the result that the wear of the barrel or container at the ends is exceedingly rapid. To protect the end walls of the container, they are lined with removable cast iron plates, but the wear of these plates is so rapid that it is necessary to dismantle the barrel with great frequency in order to replace the worn inner linings or plates, so that considerable periods of time during which the machine is inoperative, are lost in this way. By means of the present invention, the time lost in this way is so reduced, that it is no longer an important factor.

The liner wear plates which are a feature of the present invention are made in sections of such size that they can be inserted in the barrel through the dumping door opening, and the casing is provided with doors or re-

movable panels opposite the ends of the barrel, and so located that by turning the barrel, all of the bolts by which the liner plates are secured can be brought opposite the opening of the casing and conveniently tightened or removed, being thus in turn made accessible both from within the barrel and from outside the casing through the panel. This arrangement overcomes the difficulty as to frequent dismantling of the machine to replace the end liner wear plates by making it feasible to remove and replace them instantaneously while the machine is otherwise fully assembled.

Another difficulty which is overcome by the present invention is due to the tendency of the castings, particularly when long slim castings are being treated, to work into the opening around the nozzle and become wedged where they block and deflect the abrasive stream or break the nozzle, and the castings themselves are ground up and destroyed.

The liner plates of the invention overcome the second difficulty referred to in that they are provided with or more correctly provide an annular inwardly projecting shoulder surrounding the opening by which the castings are deflected away from the nozzle opening and prevented from entering therein and deflecting the abrasive and becoming ground up and injuring the nozzle as already outlined.

Another incident to the operation of sand blast barrels, as previously constructed, relates to the dumping of the cleaned castings at the end of the operation. In order to avoid dropping the castings through a considerable space, which would prove destructive to some of them, the dumping doors are made of a width in the direction of the circumference which is comparatively small, and there has been a tendency in dumping, on the part of the castings to hang in the barrel around the edges of the opening, involving the necessity for the rather awkward operation of clearing the barrel by raking the castings to and over the edge of the opening to complete the discharge. This is expensive in time.

In the present instance this difficulty has been overcome by the provision of a chute in the nature of a flat wall which fills a chord of the barrel adjacent the dumping opening, which chute in dumping prevents hanging of the castings in the barrel and avoids the

necessity for raking by providing a clean angle of flow, eliminating all obstructions. It is apparent that in the operation of the barrel the castings climb in the direction of rotation. The provision of such a filler or chute immediately adjacent the door opening in a direction of rotation, provides, when the door is at the bottom, which is the dumping position, a steep incline or chute leading to the door opening in place of the shelf or hook which hangs the castings at the edge of the door in the dumping operation as now performed.

In the accompanying drawing I have illustrated a sand blast or abrading machine barrel with liner plates and chute in accordance with the invention and portions of the casing structure, etc., which are regarded as essential to an understanding of the invention.

In the drawing—

Figure 1 is an elevation of a sand blast barrel in accordance with the invention, certain portions being broken away to illustrate the liner wear plates. The figure also shows in section the adjacent portion of the casing.

Figure 2 is a section on the line 2—2, Figure 1 looking to the left in said figure.

Figure 3 is a fragmentary section on the line 3—3 of Figure 2 on a somewhat larger scale.

Figure 4 is a more or less diagrammatic view of the apparatus in dumping position, the same being in the nature of a section on line 2—2 Figure 1.

Figure 5 is a view showing the barrel partly in front elevation and partly broken away showing a central section on the line 5—5 of Figure 4, this figure also being in dumping position.

Referring to the drawings by numerals, each of which is used to indicate the same or similar parts in the different figures, the portion of the abrading machine or sand blast apparatus illustrated comprises an outside casing or housing 1 of sheet steel and a rotary container or barrel 2.

The barrel is shown as cylindrical and provided at the ends with circular bands or tracks 3 encircling the barrel and concentric therewith, the barrel being supported and driven in rotation by rollers 4 and 5, respectively, one being a supporting and the other being a driving roller.

The heads or axial ends of the barrel are formed with openings 7 preferably concentric with the axis for the admission of the abrasive stream or blast by way of the nozzle 8 shown as mounted in the ball 9, which is in turn mounted in the rotatable supporting plate 11 as described in the applicant's co-pending application No. 79,300. This support 11 carrying the nozzle is in the form of the invention shown mounted in or on a removable panel or door 14 which closes a corresponding

opening 15 in the casing. The panel opening is a feature operating in combination with other features of the invention as hereinafter described.

The barrel or rotary container 2 is covered or protected as to the inner surfaces of the end walls 6 by removable liner wear plates 16 which are held in position by any convenient type of fastening means as bolts 17 and nuts 18 so arranged as to properly support the plates and at the same time to be accessible when the machine is assembled, from both inside the barrel and outside the housing or casing 1, the bolts being accessible from the inside by way of the barrel door opening or dumping opening 19 and from outside the barrel by way of the panel opening 15 which, as aforesaid, is opened for this purpose.

In the form of the invention shown the panel opening 15 is reinforced as to the edges of the plate 1 surrounding the opening by angle irons 21 having one leg turned outward at right angles to the plate at 22 and the other leg 24 lying flat on the outside of the plate and secured thereto. The panel 14 also has its edge portions turned outwardly in the form of a flange 25 which fits inside the flange 22 in the opening, and the flanges may, if desired, be secured together in the closed position of the panel by means of bolts 26.

In order that the liner wear plates 16 may, as explained, be removed and replaced without disassembling any other part of the machine, they are passed inside the barrel or rotary container 2 through the dumping door opening 19, and to this end the liner wear plates 16 are made in segmental sections 28 as shown to best advantage in Figure 2. The shape, size and arrangement of the plates may be widely varied. The sections should be of such dimensions that they may be passed through the opening 19 or inserted in some equivalent manner, and then turned and replaced in flat position covering the end walls. Likewise after having been released by removing the nuts 18, they may be removed through the same opening.

It will thus be apparent that the loss of time of the workmen and plant incident to removing the liner wear plates and replacing them, has been reduced to the minimum by the development of the features just described, which make it possible to instantaneously remove and replace the plates without in any way dismantling the machine. While the excessive wear at this point is a source of unavoidable expense on account of the consumption of liner plates, this is small compared to the loss of time thus reduced, and practically eliminated.

A further important feature of the improved wear plates resides in the provision of a deflecting abutment 30 adjacent the vertex of each plate or section 28 or more particularly surrounding the openings 7 at the centres

of the axial ends of the barrel and adjacent and parallel to the curved edges 31 of the wear plates. This deflecting abutment 30 is shown in the form of an annular ridge or shoulder in the casting surrounding the opening.

The abutment or shoulder serves during rotation of the barrel with consequent weaving, mixing and turning of the contents, to deflect the castings from the nozzle opening. This prevents them from interfering with the abrasive stream and also prevents them, particularly the narrow slender castings, from entering the opening between the nozzle and the edges of the barrel walls and lining where they tend to injure the nozzle and become ground up and destroyed.

Reference has already been made to the barrel door and discharge or dumping opening 19 through which the castings are removed or dropped when the operation of cleaning is completed. On account of the tracks 3 which overlie the edges of the barrel and project inwardly, and for other structural reasons, the opening does not extend the full length of the barrel. To provide a clean and smooth exit of the castings at the sides or ends where the castings might hang, the liner plate segment 33 at each end adjacent the dumping door opening 19 is deflected inwardly at this point immediately adjacent the opening, providing an inclined surface 34, see Figures 2 and 3, and the projecting portion 34 is inclined or reduced toward the centre of the barrel as shown in Figure 3 so as to provide an unobstructed passage for the castings from the ends or sides of the barrel to the discharge opening. The sides of the incline 34 are also inclined toward the opening at 35.

It will be understood that the liner plates 16 lie flat on the end walls 6 throughout the area except as to the portions 34, which form inclines leading to the door opening 19. This makes the space in the barrel at the ends beyond the door available to hold the work and at the same time disposes of all edges and supporting surfaces on the inside of the barrel which might interfere with the complete discharge of the work or product through the door opening.

The tendency of the castings in dumping to hang on the edges of the cylindrical sides of the barrel has been discussed. The discharge of the castings is facilitated by a chute 36 which is shown in the form of a flat wall 36, flattening the curve on the side of the dumping door opening 19 which is forward in the direction of rotation. The exact construction and method of producing this effect may be widely varied. The chute 36 as shown is in the form of two flat castings secured to the inside of the cylindrical wall of the barrel in any suitable manner as by radially placed bolts 37 having their heads 38 seated in suitable sockets in the inner face of the castings

and nuts 39 applied to their outer ends on the outside of the barrel. These castings 36 are placed side by side, the planes or plane 40 of their inner surfaces forming a chord corresponding to the arc of the barrel described as 70 immediately adjacent the dumping opening. In other words they present toward the inside of the barrel a flat chute surface adjacent the opening instead of the corresponding section of cylindrical wall. One edge 41 of the 75 chute or filler is immediately adjacent and coincides with the edge of the door opening.

The dumping door opening 19 is closed in the operation of the machine by a dumping door 45, the door having bars 46 extending in 80 the direction of the circumference of the cylinder. These bars project beyond the door at both ends, entering sockets 47 on the bottom side of the door, as seen in Figure 1, the opposite ends of the bars being forked at 85 48 so that they straddle projecting lugs 49 on the upper side of the door, as seen in the same figure. The forked ends are held in the closed position of the door, as shown, by pins 56 passed through suitable apertures in the 90 lugs 49.

In addition to the side door or panel 14 described, which makes the end of the barrel accessible, the machine casing 1 also has a front door opening 50 illustrated in Figure 4 95 through which the door in the drum is accessible for the admission and fastening of the liner plates and for filling. This door opening is larger than the dumping and filling opening 19 in the drawing. This opening is 100 closed by a door consisting of an arcuate plate 51 hinged at the top at 54 and a flat plate 52 connected to and depending from the arcuate plate 51, the connection being by hinges 53.

In the operation of the abrading machine, 105 the rotation of the barrel causes the castings or other members being cleaned to climb as aforesaid in the direction of rotation, so that when the barrel is stopped with the dumping opening 19 downward, which is the dumping 110 position, the portion of the load which is not directly over the door opening and therefore dumped immediately on the opening of the door, rests on or immediately above the chute 36, so that on the dropping of the portion 115 of the load referred to as over and supported by the door, the remainder of the load flows freely out of the opening, the filler or chute having the effect of removing or eliminating the shelf or curved edges immediately adjacent the dumping door opening on the up side, which in the absence of such chute, hangs the castings and makes raking necessary to clear the barrel.

With the dumping chute or filler 36 and 120 the side guides 34, the castings over the door are dropped immediately on the opening of the door and the castings which are otherwise disposed flow from the barrel, completely emptying the barrel without raking, the 130

dumping position and the position of the load at the beginning of the dumping operation being diagrammatically illustrated in Figure 4.

5 The operation of the device has been otherwise fully described in the preamble and in connection with the description of the details of the structure.

10 I have thus described a sand blast barrel embodying the features of my invention in the preferred form in order that the nature and operation of the same may be clearly understood; however, the specific terms herein are used descriptively rather than in a 15 limiting sense, the scope of the invention being defined in the claims.

What I claim and desire to secure by Letters Patent is:

20 1. In a sand blast machine having a rotary barrel with means for introducing a sand blast at the center of an axial end, an end liner plate for the barrel covering the inside surface of the opposite end, said plate being in separate sections, means for removably 25 securing each section to the end wall, a casing for the machine, the casing and barrel having door openings to admit the sections, and a door in the casing adjacent the end of the barrel to give access to the fastening 30 means from the outside.

2. In an abrading machine of the sand blast type, an outer casing having a door opening, a barrel mounted for rotation therein, the barrel having an opening in the end to admit the blast of abrasive material, and a door opening in the cylindrical side with a door for closing the same, and end liner plates covering the end walls surrounding the said end opening, said end liner plates being formed in separate 35 sections with fastening means for removably securing each section in position in the barrel, the sections and door openings being of such size, shape and proportion that the sections of liner plates may be introduced 40 through the door openings in the case and barrel, and the old liner plates removed in the same way without dismantling the machine or barrel, the casing also having an opening opposite the end of the barrel to give access to the fastening means from outside.

3. In an abrading machine of the sand blast type, a rotary barrel having an opening at the end for the admission of the sand blast, a nozzle cooperating with said opening and adjustable as to its direction, the opening being substantially larger than the adjacent portion of the nozzle to permit free adjustment of the same, the barrel having end 55 liner plates provided with an annular abutment surrounding the opening to deflect the articles being abraded from the opening during the operation of the machine.

4. In a sand blast machine, a rotary barrel having an axial opening at the end to admit the sand blast, means directing the sand blast through said opening, said means being adjustable to determine the direction of the blast and the opening being substantially larger than the directing means to permit such adjustment, and an annular abutment surrounding the opening to deflect the articles being abraded therefrom.

5. In a sand blast machine, a rotary barrel having a central opening at the end to admit the abrasive, means directing a stream of abrasive through said opening into the barrel, said means being adjustable to determine the direction of the abrasive stream and the opening being substantially larger than said directing means to provide for said adjustment, the end walls being concave from within and having an abutment surrounding the opening to deflect the articles being abraded therefrom.

6. In an abrading machine of the sand blast type, a rotary barrel having a door opening in the cylindrical side and a flat support eliminating the curve of the cylinder at the side of the door opening, which is forward in the direction of rotation forming a chute to cause the articles being abraded to flow freely from the barrel when the barrel is stopped with the door at the bottom and the latter is opened.

7. In an abrading machine of the sand blast type, a rotary cylindrical barrel having a door opening in the cylindrical side and a flat wall eliminating the curve of the cylinder at the side of the door opening, forming a chute to cause the articles being abraded to flow freely from the barrel when the barrel is stopped with the door at the bottom and the latter is opened, the chute comprising a removable casting and means for removably securing the same to the inside of the cylinder in the position described.

8. A rotary sand blast barrel having a dumping door opening in the side surface, and inclined walls adjacent each end of the barrel leading castings to the door, and a flat wall at the side of the door, the latter providing a chute to assist the castings in flowing from the barrel through the door opening.

9. In a rotary sand blast barrel having end walls, side walls with a dumping opening therein, the end walls having portions on each corresponding side of the door opening and leading to the opening which are inclined at an angle to the remaining portion of the 115 end walls to assist in the dumping operation, said portions terminating at the edge of said opening.

Signed by me at Hagerstown, Maryland, this 2 day of January, 1926.

FOSTER J. HULL.
